UNITED STATES PATENT OFFICE.

DONALD O. SHIVELY, OF HOUSTON, TEXAS.

SAFETY APPLIANCE FOR STREET CARS.

1,425,062.

Specification of Letters Patent. Patented Aug. 8, 1922.

Application filed August 5, 1921. Serial No. 490,103.

To all whom it may concern:

Be it known that I, DONALD O. SHIVELY, a citizen of the United States, residing at Houston, in the county of Harris and State 5 of Texas, have invented certain new and useful Improvements in a Safety Appliance for Street Cars, of which the following is a specification.

This invention relates to new and useful 10 improvements in a safety appliance for street cars.

One object of the invention is to provide an appliance of the character described connected to the air brake system, of a street 15 car, and actuated by the fender trip, whereby the air will be applied to the brakes and the brakes applied, when the trip is actuated.

Another object is to provide an attachment 20 of the class described through which the brakes will be automatically applied when the fender trip strikes an object on the track in front of the car.

With the above and other objects in view 25 the invention has particular relation to certain novel features of construction, operation and arrangement of parts, an example of which is given in this specification and illustrated in the accompanying drawings, 30 wherein:—

Figure 1, is a fragmentary vertical sectional view of the front end of a street car showing my attachment applied thereto, and,

Figure 2, shows a diagrammatic view of 35 the air brake system of street car showing my improvement thereto.

Referring more particularly to the drawings the numeral 1, designates the car, 40 which has the floor 2. Depending from the front end of the car are the brackets 3, one on each side. A bearing rod 4 has its ends anchored to these brackets and the depending fender trip 5 is swung on said rod. This 45 trip extends entirely across the car and just clears the track 6. It is of the usual and well known construction.

Behind this trip there is the usual fender 7 which extends entirely across the track. 50 It is formed of the wings 7', 7' at right angles to each other, one being normally vertical and the other horizontal. It is pivoted between the depending side brackets 8, 8 which are secured to the bottom of the car. 55 A latch 9 is pivoted to one of the brackets 8 and one end then engages over the upper

edge of the vertical wing 7'. The other end of this latch is turned downwardly and one end of the release rod 10 is pivoted thereto. The other end of this rod is pivot- 60 ed to the arm 11 which is fixed to, and up- stands from, the rod 4. A strong pull spring 12 is attached, at one end, to the vertical wing 7' and at its other end it is at- tached to the car floor in front of the fender. 65

The numeral 13 designates the re-set rod. This rod is pivoted at one end, to the vertical wing 7' and at its other end to the upper end of the re-set lever 14. This lever is pivoted to one of the brackets 3 and its 70 lower end is curved rearwardly. The push rod 15 is pivoted at its lower end to the curved end of the lever 14 and its upper end works through a bearing in the car floor and is formed with a pedal by means 75 of which it may be depressed by the foot of the motorman. When the trip 5 strikes an object on the track it is forced rearwardly, carrying the arm 11 forwardly and ex- erting a forward pull on the release rod 10. 80 This releases the latch 9 and the fender will then be tilted forwardly by the pull spring 12. The horizontal wing 7' will drop down on the track and pick up the object and pre- 85 vent it from being run over by the wheels 85 behind the fender. The fender is of a basket like structure and large enough to hold the human body or object of like size.

The fender is reset by depressing the 90 push rod 15. When this rod is depressed the reset lever 14 will exert a rearward thrust to the re-set rod 13 and this will re- store the fender to original position. The upper edge of the vertical wing 7' will 95 strike against the bevelled end of the trig- ger 9 and elevate said end into position to engage over the upper edge of said wing. As the trigger is elevated a forward thrust will be imparted to the release rod 10 and this will operate through the arm 11 to re- 100 store the trip 5 to original position.

The street car is equipped with the usual air system which includes a main reservoir 16 and the usual air tubes or pipes. The construction and arrangement of this sys- 105 tem is well known and need not be described in detail. It includes, however, the safety air line 17, and the main air line 18, which leads to the reservoir 16.

The safety air line is connected into one 110 end of the valve cylinder 19 through the pipe 20 and the main air line 18 is connected

into the side of said cylinder through the pipe 21. Within the cylinder 19 there is a sliding plunger-like valve 22 which normally cuts off communication between the 5 pipes 20 and 21 as shown in Figure 1. The valve 22 is fixed to a stem 23. An actuating rod 24 is connected, at one end, to the free end of the arm 11 and its other end is attached to a pull spring 25 which is connected to the bottom of the car. This rod is also connected to the valve stem. When the trip 3 strikes an object a pull is exerted through the rod 24 and the stem 23 and the valve is pulled outwardly in the cylinder 19 10 beyond the pipe 21 thus connecting the main air line with the safety air line and the emergency brakes will be thereby applied and the car at once stopped.

What I claim is:—

20 1. The combination with a street car of a rotatable transverse bearing rod carried by the front end of the car, a fender trip depending from said rod, a fender depending from the car behind said trip formed with 25 wings extending at substantially right angles to each other, said fender being pivotally mounted and extending entirely across the railway track, a latch pivoted to the car, one end of which is upwardly beveled and 30 notched to engage over the edge of one of said wings, and an arm fixed to and upstanding from said rod, a release rod pivoted at one end to the other end of said latch and pivoted at its other end to said 35 arm, a pull string attached at one end to said last mentioned wing of the fender and attached at its other end to the car in front of the fender, a reset rod pivoted at one end to said last mentioned wing, a reset lever pivoted to a suitable bracket carried by the front end of the car the other end of said 40 reset rod being pivoted to the upper end of said reset lever, a push rod working through a bearing in the car floor and pivoted at its lower end to the other end of said reset 45 lever, and whose upper end is formed into a pedal, an airbrake system embodied in the car and including a main air line, and a safety air line, a valve normally blocking communication between said lines, and a connection between said fender trip and valve whereby the movement of the former will actuate the latter to establish communication between said lines.

lever, and whose upper end is formed into a pedal.

2. The combination with a street car of a rotatable transverse bearing rod carried by the front end of the car, a fender trip depending from said rod, a fender depending from the car behind said trip formed with wings extending at substantially right angles to each other, said fender being pivotally mounted and extending entirely across the railway track, a latch pivoted to the car, one end of which is upwardly beveled and notched to engage over the edge of one of said wings, and an arm fixed to and upstanding from said rod, a release rod pivoted at one end to the other end of said latch and pivoted at its other end to said arm, a pull spring attached at one end to said last mentioned wing of the fender and attached at its other end to the car in front 65 of the fender, a reset rod pivoted at one end to said last mentioned wing, a reset lever pivoted to a suitable bracket carried by the front end of the car the other end of said reset rod being pivoted to the upper end of 70 said reset lever, a push rod working through a bearing in the car floor and pivoted at its lower end to the other end of said reset lever, and whose upper end is formed into a pedal, an airbrake system embodied in the 75 car and including a main air line, and a safety air line, a valve normally blocking communication between said lines, and a connection between said fender trip and valve whereby the movement of the former 80 will actuate the latter to establish communication between said lines.

In testimony whereof I have signed my name to this specification in the presence of two subscribing witnesses.

DONALD O. SHIVELY.
